Primary Examiner — Mark A Goodwin(74) *Attorney, Agent, or Firm* — Global IP Counselors,
LLP(57) **CLAIM**

The ornamental design for a tiller, as shown and described.

DESCRIPTION

FIG. 1 is a front, left, and top perspective view of a tiller in accordance with our new design;

FIG. 2 is a rear, right, and top perspective view of the tiller in accordance with our new design;

FIG. 3 is a front elevational view of the tiller in accordance with our new design;

FIG. 4 is a rear elevational view of the tiller in accordance with our new design;

FIG. 5 is a top plan view of the tiller in accordance with our new design;

FIG. 6 is a bottom plan view of the tiller in accordance with our new design;

FIG. 7 is a left side elevational view of the tiller in accordance with our new design; and,

FIG. 8 is a right side elevational view of the tiller in accordance with our new design.

The broken lines in the drawings illustrate portions of the tiller which form no part of the claimed design.

1 Claim, 8 Drawing Sheets(56)
